UNITED STATES PATENT OFFICE.

JOSEPH F. OBERT, OF MILLCREEK, PENNSYLVANIA.

PAPER-MAKING MACHINE.

SPECIFICATION forming part of Letters Patent No. 724,732, dated April 7, 1903.

Application filed December 15, 1902. Serial No. 135,267. (No model.)

To all whom it may concern:

Be it known that I, JOSEPH F. OBERT, a citizen of the United States, residing at Millcreek, in the county of Erie and State of Pennsylvania, have invented new and useful Improvements in Paper-Making Machines, of which the following is a specification.

This invention relates to paper-making machines; and it consists in certain improvements in the construction thereof, as will be hereinafter fully described, and pointed out in the claims.

Heretofore there has been used in paper-making machines what is known as a "doctor" for keeping the rolls clear of any material that may be taken up by the rolls as the paper is passed through them in the process of manufacture. Heretofore no provision has been made for taking care of the accumulation on the doctor, so that it required constant attention to prevent droppings from the accumulation onto the incoming sheet. Such dropping injures the roll, the product, and the web carrying the product, and such accumulations on the roll give it such weight as to injure the roll. To obviate this difficulty is among the objects of this invention.

The invention is illustrated in the accompanying drawings, as follows:

30 Figure 1 shows a perspective view of my preferred construction; Fig. 2, a side elevation, partly in section, of an alternative construction.

A A mark the rolls, and the broken lines 35 B B the line of paper upon which the rolls are arranged to operate. The doctor C is arranged in its usual position, so as to prevent anything carried up by the upper roll from passing around and into the nip. Immediately back of the doctor is a trough, into which accumulations on the doctor pass. A conveyer E of any desired construction is arranged in the trough. I prefer, however, the construction shown in Fig. 1, wherein the conveyer is in the form of a belt e. This belt is 40 carried at one end by the spool e'. The spool is mounted in the bracket e². The opposite end of the belt is carried by the spool e³, carried by the bracket e⁴. The spool e³ is driven 45 by the gear e⁵, which is driven by the gear e⁶. These are driven from the shaft e⁷ and the driving-pulley e⁸, which may be run from any convenient source of power. I prefer provid-

ing the rear of the trough with the elevated side E² to prevent any accumulation dropping 55 over the back of the trough.

I prefer that the doctor and conveyer be arranged on one frame. These are carried by the trunnions E' E'.

The operation of the device can be readily 60 understood from the drawings. The matter accumulating on the doctor C passes on to the conveying-belt e and is carried to the side of the machine and dropped. In this manner any accumulation is prevented, and consequently 65 there can be no dropping on the incoming paper. Furthermore, the weight of the doctor is kept substantially uniform.

In the alternative construction shown in Fig. 2 the doctor C' has the apron C² extending from it and is supported by the trunnion C³. The conveyer E⁵ is arranged in a separate frame E⁴ from that of the doctor. Its purpose and general operation are the same as that of the construction shown in Fig. 1. 75

What I claim as new is—

1. In a paper-making machine, the combination with the rolls and a doctor thereon, said doctor being arranged out of the normal path of the paper; of a conveyer arranged to 80 remove the matter caught by the doctor and to carry the matter so caught away from the paper passing through said rolls.

2. In a paper-making machine, the combination with the rolls and a doctor thereon; of 85 a conveyer carried with the doctor and arranged to remove the matter caught by the doctor.

3. In a paper-making machine, the combination with the roll A of the doctor C; the 90 trough D; the conveyer arranged in the trough; the trunnions E' E' supporting the trough and doctor.

4. In a paper-making machine, the combination of the roll A; the doctor C arranged 95 thereon; the trough D; the belt conveyer E arranged in the trough; and the trunnions E' E' for carrying the trough, conveyer and doctor.

In testimony whereof I have hereunto set 100 my hand in the presence of two subscribing witnesses.

JOSEPH F. OBERT.
